Specification for Design.

Patented Oct. 8, 1912.

Application filed August 23, 1911. Serial No. 645,661. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Berth-Light Fixtures, of which the following is a specification.

The nature of my design is fully illustrated in the accompanying drawing, to which reference is made, and in which,

Figure 1 represents a front elevation of the design; Fig. 2 represents a side elevation of the design; and Fig. 3 is a plan view of the design.

My design comprises an upright base por-

tion having a generally flat front face, the sides receding and converging, together with a convex portion at the upper portion of the base and disposed on the front face thereof, the sides of the convex portion extending downwardly toward and merging into the base portion, having the contour and relative proportion of parts shown.

I claim:

The ornamental design for a berth light fixture as shown and described.

LINDSLEY SCHEPMOES.
